[57] ABSTRACT

The clamp is mounted within a reverberation unit so as to hold reverberation springs in place during transportation. The clamp is actuated by pushing an actuator into the unit so as to deflect a leaf spring and bring a channel-shaped holder thereon into restraining position about the reverberation springs. Movement of the actuator out of the unit allows the leaf spring to flatten and the holder to be moved away from the reverberation springs.

CLAMP FOR A REVERBERATION UNIT

This invention relates to a clamp for a reverberation unit. More particularly, this invention relates to a clamp for the springs of a reverberation unit.

Heretofore, various types of reverberation units have been constructed in order to introduce reverberation effects in music and particularly for use in electrical musical instruments such as guitar amplifiers and electronic organs. Generally, these reverberation units have relied upon the use of helically coiled springs of relatively long length to transmit a vibration to produce the desired effect. However, during transportation of the reverberation units from place to place as in shipment of the reverberation units from a point of sale to a customer, these springs have frequently been damaged and have been rendered incapable of proper functioning.

While it has been known to clamp the reverberation springs of a reverberation unit for transporting purposes with various types of devices, such as cam actuated bars or strips which have rubber blocks thereon for engaging against the springs, the devices have been of complex construction. Further, such devices have relied on a number of components in order to bring about the clamping of the reverberation springs. Also, in some instances, as these devices have been substantially fully enclosed within the housing of the reverberation unit, the clamping position of such devices cannot be easily or readily determined, in which case the springs can still be damaged through a neglect to secure the springs with the clamping devices.

Accordingly, it is an object of this invention to restrain the springs of a reverberation unit against damaging oscillations.

It is another object of this invention to provide a clamp for reverberation units which is simple both to make and to use.

It is another object of the invention to readily distinguish a clamping position from a non-clamping position of a clamp for the springs of a reverberation unit.

It is another object of the invention to actuate a clamp for a reverberation unit in a simple push-pull manner.

It is another object of this invention to support the coils of a reverberation unit in a manner to prevent damaging oscillations and mechanical stresses therein.

Briefly, the invention provides a clamp for a reverberation unit in which the coil springs of the unit are clamped against damaging oscillations. The clamp includes a resilient elongated member such as a leaf spring or cable spring which is fixed at one end with respect to the reverberation unit and which carries a means at its opposite end for flexing the member and securing it in a flexed or buckled condition. The clamp also has a holder mounted on the leaf spring which is sized to envelop the coil springs within the reverberation unit. The means for flexing and securing the member includes an actuator plate having a handle for pushing the plate longitudinally of the elongated member to flex the same, and an L-shaped slot which cooperates with a stud secured to a mounting plate of the reverberation unit to maintain the member in a flexed condition.

The actuator plate is mounted so as to slide relative to the stud and in order to utilize the clamp is initially moved into the reverberation unit. This causes the leaf

spring which is initially in a flat condition to flex upwardly within the reverberation unit to bring the holder into enveloping relationship with the coil springs. The holder thus serves to confine the springs to a limited space so that large oscillations are avoided when the unit is transported or otherwise moved. In order to release the coil springs, the actuator plate is released from engagement with the stud in the L-shaped slot of the plate so that the actuator plate slides under the force of the spring outwardly of the stud and the reverberation unit to return the spring to a flattened condition. The clamp thus serves to eliminate large oscillations in the reverberation unit coil springs and restrain the springs in position during transportation.

These and other objects and advantages of the invention will become more apparent from the following description and appended claims taken in conjunction with the accompanying drawings in which:

FIG. 1 illustrates an exploded perspective view of a reverberation unit incorporating a clamp according to the invention;

FIG. 2 illustrates an exploded cross-sectional end view of the reverberation unit and clamp of FIG. 1 prior to assembly;

FIG. 3 illustrates a view similar to FIG. 2 of the clamp in an initial unflexed position with respect to the coil springs of the reverberation unit;

FIG. 4 illustrates the clamp in flexed condition in restraining relation to the coil springs of the reverberation unit; and

FIG. 5 illustrates a fragmentary perspective view of a modified clamp according to the invention in a flexed condition.

Referring to FIGS. 1 and 2, the reverberation unit 10 is constructed of known construction. For example, the reverberation unit 10 has a box-like housing 11 from which a pair of mounting flanges 12, 13 extend outwardly. The housing 11 supports a channel-shaped strip 14 therein, for example, in a suspended manner by a plurality of springs 15 at the ends of the channel-shaped strip 14. The channel-shaped strip 14 carries a driver 16 at one end and a pickup (not shown) at the opposite end which are of known construction. A pair of helically-coiled springs 18 are mounted between the driver 16 and pickup in a stressed or tensioned manner. The mounting flanges 12, 13 are each provided with a plurality of holes 19 which serve to facilitate the mounting of the reverberation unit on a mounting plate 20.

The mounting plate 20 is provided with a plurality of bolts 21 which are positioned so as to pass through holes 19 in the flanges 12, 13 of the reverberation unit 10 and cooperate with suitable locking nuts 22 (FIG. 4) to secure the reverberation unit housing 11 to the mounting plate 20.

Referring to FIG. 1, in order to restrain the springs 18 during transportation of the reverberation unit 10 from place to place, a clamp 23 is provided. This clamp 23 includes a self-supporting elongated member or strip 24, for example, a flexible resilient leaf spring of metallic material, which is secured as by rivets 25 at one end to the mounting plate 20 outside of and approximately at the mid-point of the reverberation unit housing 11. In addition, the clamp 23 has a channel-shaped holder 26, for example formed of metallic

material, which is secured or mounted intermediately of the member 24. The holder 26 is mounted so that the flanges 27 thereof extend upwardly from the member 24 and are positioned within the plane of the channel-shaped strip 14 of the reverberation unit 10. The clamp 23 is also provided with a means 28 for selectively securing the member 24 in a flexed condition, with the holder 26 disposed in a displaced position in restraining relation to the springs 18 of the reverberation unit 10. For example, the means 28 includes an actuator plate 29 which is secured to the end of the member 24 opposite the end fixed to the mounting plate 20. This actuator plate 29 is of substantially rectangular configuration with an L-shaped profile and includes an upstanding flange 30 which may be provided with a slot 31 and which serves as a handle portion for pushing of the plate 29 longitudinally of the axis of the flexible member 24 and toward the reverberation unit housing 11. The plate 29 also has a slot 32 of substantially L-shaped configuration which cooperates with a stud 33 secured to the mounting plate 20. The stud 33 extends upwardly through the slot 32 in the actuator plate 29 and is slidably received therein. The slot 32 and stud 33 are dimensioned to maintain the flexible member 24 in a flattened condition or a flexed condition with respect to the mounting plate 20. In the flattened condition of the member 24, the stud 33 is disposed in the forward end of the L-shaped slot 32. In this position, the member 24 is held in a slightly flexed or bent shape (FIG. 2). In the flexed condition of the member 24, the stud 33 is disposed in the rear end of the slot 32 within the short leg defined thereby in abutting relation so that the flexible member 24 is held in the flexed position. As shown, the stud 33 can be formed by a threaded member 34 passing into the mounting plate 20 and a washer 35 held against the plate 29 in slidable relation by the threaded member 34.

In order to transport the reverberation unit 10 and restrain the springs 18 against oscillations which may be detrimental to the springs 18, the reverberation unit 10 is first disposed over the mounting plate 20 (FIG. 2). At this time, the flexible member 24 of the clamp 23 is in a substantially flattened condition with the holder 26 disposed within the plane of the channel-shaped strip 14 of the reverberation unit 10. Next (FIG. 3), the reverberation unit housing 11 is brought down onto the mounting bolts 21 on the mounting plate 20 so that the bolts 21 align with the holes 19 in the mounting flanges 12, 13 of the housing 11. The locking nuts 22 are then threaded onto the bolts 20 so as to secure the housing 11 to the mounting plate 20. Thereafter, the actuator plate 29 is pushed towards the housing 11, that is, longitudinally of the axis of the flexible member 24. This causes the flexible member 24 to flex, or buckle, at an intermediate location so that the channel shaped holder 26 is brought up into the channel strip 14 in restraining relation to the springs 18. It is noted that the degree of flexing of the flexible member 24 and the size of the holder 26 are such that the springs 18 are not contacted by the holder 26 are such that the springs 18 are not contacted by the holder 26 but are slightly spaced therefrom. The slight spacing is sufficient to damp out any large oscillations of the springs during transportation while otherwise permitting slight oscillations which would not otherwise be detrimental to the reverberation unit.

As the actuator plate 29 slides along the mounting plate 20 to bring the holder 26 into position, the stud 33 becomes aligned adjacent the short leg of the slot 32. The actuator plate 29 is then moved sidewise so as to bring the stud 33 within the confines of the short leg of the slot 32. The stud 33 then abuts the actuator plate 20 within the slot 32 so as to maintain the flexed condition of the member 24 and the position of the holder 26 (FIG. 4).

10 In order to release the clamp 23 from restraining relation with respect to the reverberation springs 18, the handle portion 30 of the actuator plate 29 is grasped and moved so that the stud 33 is aligned with the longer leg of the slot 32. The elongated member 24 is then moves outwardly under the stored spring force so that the member 24 flattens. This moves the holder 26 out of position with respect to the reverberation unit springs 18. The reverberation unit 10 can then be used in this position or removed from the mounting plate 20 entirely in a known manner.

15 It is noted that the flexible member 24 of the clamp 23 is disposed in a slightly bent or flexed shape when in the flattened position. This is intended to insure that 20 the member 24 is flexed away from the mounting plate 20 upon movement of actuator plate 29 towards the reverberation unit 10. Further, the mounting of the elongated member 24 in this prestressed condition is brought about by the relative placement of the rivets 25 25 used to secure the member 24 to the mounting plate 20 and the stud 33 with respect to the slot 32 in the actuator plate 29.

20 Referring to FIG. 5, wherein like references are used to indicate like parts as above, the clamp 40 can alternatively be constructed with a cable-type spring which facilitates bending or routing about a corner. In such a case, the clamp 40 has a flexible cable spring 41 which is disposed on the mounting plate 20, for example, in an L-shaped pattern or other pattern with a bend. The cable spring 41 includes a guide tube 42 and a spring wire 43 slidably mounted within the tube 42. The tube 42 is fixed to the mounting plate 20 in any suitable manner for a distance from a free end outside the reverberation housing 11 to a point under the mounting flange 13 of the housing 11 and extends from the free end to a point adjacent a holder 26 fixed on the spring wire 43 under the channel shaped strip 14 in the housing 11. The spring wire 43 is fixed at one end remote 45 from the tube 42 as by rivets 25 and carries a knob 44 near the opposite end. The knob 44 extends through an L-shaped slot 45 in the guide tube 42 so as to be movable longitudinally of the tube 42.

45 In operation, in order to raise the holder 26, the knob 50 44 is pushed forwardly in the slot 45. This causes the spring wire 43 to slide relative to the guide tube 42 and to flex in the region within the housing 11. The flexing action, as above, brings the holder 26 into restraining relation with the springs 18. In order to lock the spring wire in place, the knob 44 is moved laterally into the short leg of the slot 45. Alternatively, the knob 44 can be locked in place in any other suitable manner, as is known.

55 60 65 In order to release the cable spring 41, the knob 44 is pulled back to the initial position in the slot 45. This causes the spring wire 43 to unflex and flatten thereby lowering the holder 26.

The cable-type spring clamp allows bending or routing around corners and thus can be mounted on the mounting plate, as shown, or by being disposed on a side wall of a mounting box (not shown) which supports the reverberation unit on a top surface.

It is noted that various materials and shapes can be used for the various components of the clamp of the invention. For example, the elongated member which is of a self-supporting resilient flexible material may be made of metal plastic materials. Also, the holder may be made of similar material and may be shaped in any suitable manner so as to restrain the springs of the reverberation unit against detrimental oscillations. The actuator plate or knob may also be made of various materials such as metal, plastic and the like and of any suitable shape. Alternatively, the flexible member may be provided with a handle instead of the actuator plate which would cooperate with a slot, for example, an L-shaped slot, in the mounting plate so as to be selectively moved into one or two positions to hold the elongated member in the flattened and flexed conditions.

The invention thus provides a clamp for a reverberation unit which can be produced in a simple manner and which can be utilized in a relatively simple manner. Further, the clamp of the invention insures against the large scale oscillations of the coil springs of the reverberation units which have in the past caused damage to the reverberation units.

The invention further provides a clamp which restrains the reverberation coils of a reverberation unit at their midpoint so as to reduce amplitudes of oscillation and the possibility of damage.

It is noted that the clamp can be mounted at either point of the reverberation unit. Alternatively, the reverberation unit can be provided with more than one clamp and such can be mounted at various points along the reverberation unit to restrain the reverberation springs.

What is claimed is:

1. A clamp for a plurality of springs of a reverberation unit comprising a flexible self-supporting elongated member adapted to be secured at one end in fixed relation to the reverberation unit, a holder mounted intermediately of said member, and means at an opposite end of said member for selectively securing said member in a flexed condition with said holder disposed in a displaced position in restraining relation to the springs of the reverberation unit.

2. A clamp as set forth in claim 1 wherein said holder is channel-shaped and extends outwardly of said member.

3. A clamp as set forth in claim 1 wherein said means includes an actuator plate secured to said member, said plate having a handle portion thereon for pushing of said plate longitudinally of said member for flexing of said member.

4. A clamp as set forth in claim 3 wherein said plate includes an L-shaped slot therein and said means further includes a fixedly mounted stud slidably mounted in said slot for engaging said plate to maintain said member in a flexed condition.

5. A clamp as set forth in claim 1 wherein said member includes a guide tube and a spring wire slidably mounted within said tube, said spring wire mounting said holder thereon.

10 6. A clamp for a plurality of springs in a reverberation unit comprising an elongated strip of self-supporting material, a channel-shaped holder mounted intermediately on said strip, an actuator plate secured to one end of said strip for movement longitudinally of the axis of said strip to cause flexing of said strip and movement of said holder into a displaced position in restraining relation to the springs of the reverberation unit.

15 7. A clamp as set forth in claim 6 wherein said strip is made of metal.

20 8. In combination with a reverberation unit having at least one spring mounted under tension; a clamp comprising a flexible member secured at one end with respect to said unit, a holder mounted intermediately of said member within said unit, and means at the opposite end of said member for flexing said member to displace said holder into restraining relation with said springs.

25 9. The combination as set forth in claim 8 which further includes a mounting plate mounting said unit and said member thereon and wherein said means includes a stud secured to said mounting plate and an actuator plate secured to said member, said plate having an L-shaped slot therein slidably receiving said stud therein whereby movement of said plate towards said unit flexes said member and abutment of said stud with said slot maintains said member in flexed condition to position said holder in restraining relation to said springs.

30 10. The combination as set forth in claim 8 wherein said holder is channel shaped.

40 11. The combination as set forth in claim 8 wherein said member is a leaf spring of metal.

35 12. The combination as set forth in claim 8 wherein which further comprises a guide tube slidably mounting said member therein between said holder and said means.

45 13. The combination as set forth in claim 12 wherein said guide tube is mounted in a bent pattern with respect to said unit for guiding said member about a bend.

50 14. The combination as set forth in claim 12 wherein said means includes a knob carried on said member and projecting through an L-shaped slot in said guide tube, said knob being slidable within said slot to move said member between a flattened position and a flexed position within said unit.
